A. DE PARADE.

BROOM MOISTENER.

APPLICATION FILED SEPT. 21, 1918.

1,322,766.

Patented Nov. 25, 1919.

UNITED STATES PATENT OFFICE.

ALBERT DE PARADE, OF CORDELL, OKLAHOMA.

BROOM-MOISTENER.

1,322,766.

Specification of Letters Patent. Patented Nov. 25, 1919.

Application filed September 21, 1918. Serial No. 255,017.

To all whom it may concern:

Be it known that I, ALBERT DE PARADE, a citizen of the United States, residing at Cordell, in the county of Washita and State 5 of Oklahoma, have invented new and useful Improvements in Broom-Moisteners, of which the following is a specification.

This invention relates to moistening or dampening devices for brooms, and its purpose is to provide readily attachable means 10 for the ordinary fiber broom which will deliver, during the act of sweeping, a moistening or dampening fluid to the active or sweeping fibers of the broom in order to lay 15 and collect the dust ordinarily raised during sweeping.

The result in view is accomplished by means of a fluid container adapted to be hung or mounted upon the broom and preferably nested within the fibers thereof, the 20 said container being provided with drip openings and a feeding channel which will deliver the fluid to such openings, means being provided to insure the proper ejection of 25 the fluid and distribution thereof to the broom fibers.

In order that the invention may be understood by those skilled in the art, I have illustrated herein one embodiment of the same, 30 but it will be understood that the disclosure is purely illustrative and in no sense restrictive of the invention, as it may be varied mechanically within a considerable range without departing from the spirit of the invention.

In the accompanying drawing,—

Figure 1 is a view in side elevation of a moistener made in accordance with my invention, the broom being shown in dotted 40 lines.

Fig. 2 is a view in end elevation of the moistener.

Fig. 3 is a sectional view, vertically, through the moistener on a slightly enlarged 45 scale,

Figs. 4 and 5 are perspective views of the device, the distributor being removed for clearness of illustration.

Referring to the drawings by numbers, 50 like numbers indicating like parts in the several views, 10 indicates a broom of any ordinary or desired construction, the one shown being of the ordinary broom corn fiber type having the free sweeping ends and the 55 stitched together and bunched ends which

form the head of the broom and are secured to the handle in the usual manner.

Nested within the free ends of the broom fibers, as herein disclosed, is the fluid container 11, which is preferably of substantially elliptical shape in cross section as here shown and of such a length that it may be conveniently located within the broom, as shown, the said container 11 having attached to the ears 12 the hangers 13, preferably 60 formed, as shown, of wire and provided at their upper ends with hooks 14 adapted to engage a row of stitching 15 so as to suspend the container 11 within the broom, in the manner shown, and while I preferably nest the device within the broom fiber, it will be understood that it can, if desired, be located and hung on the outside of the broom.

The container 11 is provided with a filling aperture or nozzle closed by a suitable airtight cap 16, this nozzle being preferably at the lower corner of the container 11 so that the broom may be turned with the fibers upward, the fibers parted so as to give access to the container, and the cap removed for 75 convenient filling of the container 11. The bottom of the container 11 is provided with one or more apertures 17 through which the moistening fluid, whether it be water or oil, may drip, and these drip openings communicate with a relatively narrow compartment 18 at one side of the container 11, the compartment 18 being formed by a partition 19, which extends from the bottom of the container 11 to a point near the top thereof, its 80 ends being secured to the end walls of the container 11 so as to divide said container into a main fluid-containing compartment 18 and a smaller fluid-feeding compartment.

The purpose of dividing the main and 85 supplemental compartments is to insure a proper feed from the compartment 18 to the drip openings 17, and avoid the likelihood of a flooding of the broom fibers by an excessive feed of fluid as would be the case if the 90 drip openings 17 communicated directly with the main compartment. The fluid feeds from the main compartment into the feeding compartment 18 by reason of the dash- 95 ing of the fluid up the curved wall of the container and over the top of the partition 19, so that a constant supply of fluid, sufficient for feeding the broom fibers, is insured in the small compartment.

In order that the fluid may be forced 100

through the drip openings 17 from the airtight container, I rely on the bending action of the broom fibers in compressing the side walls of the container during use of the 5 broom, the side walls being provided, as shown in Fig. 4, with compressing rods 20 which are secured in any suitable manner, as by the clips 21, with their ends preferably projecting slightly away from the walls so 10 that as the broom is bent in use sufficient pressure will be exerted to expel, by reason of buckling of the side walls, the fluid through the drip openings 17. In Fig. 5, I have shown a construction in which the compression rods are dispensed with and the 15 side walls are stiffened by forming an integral rib 22 in the wall, which rib is of such length as to give a rigid centrally-disposed portion to form a compression member under the bending action of the broom without interfering with the flexibility of the wall, so as to buckle the walls sufficiently to expel the fluid from the small compartment 18 through the drip openings 17. 20

In order that the fluid may be evenly distributed, I provide below the container 11 a distributor 23 which is shown in the present instance as made of sponge, although it is obvious that any fibrous or felted material 25 could be used, the distributor 23 extending lengthwise beneath the bottom of the container 11 and in close contact therewith so as to receive the fluid fed through the openings 17. The said distributor 23 is supported 30 upon a shelf 24, which shelf is preferably adjustably and tiltingly mounted upon a rod 25, which passes centrally beneath the shelf 24, traversing struck-out clips 26 in the shelf 24 so as to form a support therefor, 35 the said rod 25 being pivotally mounted at one end in an ear 27 depending from the container 11, and at its other end being pivotally mounted in a screw eye 28 passing through an ear 29 secured to the container 40 and having a winged adjusting nut threaded on its upper end so that the shelf 24 may be raised and lowered to vary its clamping action upon the distributor 23. The edges 45 of the shelf 24 are preferably turned outwardly and downwardly, as shown, so that as the broom is used and the fibers are forced against the edge of the shelf it will tilt and squeeze the sponge alternately on opposite edges thereof, forcing the fluid from the distributor 23 out into the fibers of the broom 50 down which the fluid will trickle so as to keep them in properly moistened condition.

From the foregoing it will be seen that a moistener is provided which will feed the 60 fluid in limited quantities by means of the small feeding compartment to the drip openings when the broom is in use, and that by means of the distributor mounted in the manner described the fluid fed to it through 65 the drip openings will be automatically

forced out when the broom is in use and delivered to the fibers on each side of the broom, thus insuring a regular and steady supply while the broom is in use.

It will be understood that such mechanical variations as expediency may suggest from what is here shown may be made and still be within the range of my invention, and I do not, therefore, limit myself to the details of construction herein set forth. 75

I claim:

1. In a device of the class described, the combination of a container having a discharge opening, a compressible distributor to receive fluid from said opening, and means 80 to compress said distributor and discharge fluid therefrom to the broom fibers and hooks to suspend the container within the broom.

2. In a device of the class described, the combination of a container having a discharge opening, a distributor to receive fluid from said opening, and movable means in the path of movement of, and actuated by the bending of, the broom fibers to discharge 90 fluid from said distributor to the broom fibers, and detachable hooks to suspend said container within the broom fibers.

3. In a device of the class described, the combination of a container having a discharge opening, a distributor of compressible and absorbent material to receive fluid from said discharge openings, and removable means actuated by the bending of the broom fibers to squeeze the fluid from said 100 distributor and discharge it to said broom fibers. 95

4. In a device of the class described, the combination of a container having a discharge opening, a compressible and absorbent distributor to receive fluid from said discharge opening, and a supporting shelf for said distributor movable under the bending action of the broom fibers to squeeze said distributor and discharge fluid therefrom to the broom fibers. 105 110

5. In a device of the class described, the combination of a container having a discharge opening, a compressible and absorbent distributor to receive fluid from said opening, and a tilting supporting shelf for said container movable under the bending action of the broom fibers to compress said distributor and discharge fluid therefrom to the broom fibers. 115 120

6. In a device of the class described, a container having discharge openings, a compressible and absorbent distributor to receive fluid from said openings, and a centrally pivoted supporting shelf for said distributor 125 tiltable in opposite directions under the bending action of the broom fibers to squeeze opposite portions of said distributor and discharge the fluid therefrom to the broom fibers. 130

7. In a device of the class described, the combination of a container adapted to be nested in a broom and having yielding sides and discharge openings, a distributer to receive fluid from said openings and discharge it to the broom fibers, and a relatively rigid compressing member to receive the action of the broom fibers and compress said yielding sides to discharge fluid to said distributer.

8. In a device of the class described, the combination of a container adapted to be nested in a broom and having yielding sides and discharge openings, a distributer to receive fluid from said openings and discharge it to the broom fibers, and a relatively rigid rod secured to the side of the container to receive the action of the broom fibers and

compress said yielding sides to discharge fluid to said distributer.

9. In a device of the class described, the combination of a container having a main fluid compartment and a fluid feeding compartment separated by an open-topped partition, said feeding compartment having discharge openings, a distributer to receive fluid from said openings, and adjustable means for clamping said distributer in place.

In testimony whereof I have hereunto set my hand in presence of two subscribing witnesses.

ALBERT DE PARADE.
